UNITED STATES PATENT OFFICE.

ALBERT ANGELL, OF EAST ORANGE, NEW JERSEY, ASSIGNOR OF ONE-HALF
TO ISAAC TEICHMAN, OF NEW YORK, N. Y.

COMBINED CIGAR CUTTER AND PERFORATOR.

SPECIFICATION forming part of Letters Patent No. 331,366, dated December 1, 1885.
Application filed February 16, 1885. Serial No. 156,018. (No model.)

To all whom it may concern:

Be it known that I, ALBERT ANGELL, of 5
East Orange, in the county of Essex and State
of New Jersey, have invented an Improvement
in Combined Cigar Cutter and Perforator, of
which the following is a specification.

The object of this invention is to perforate
the cigar transversely near the tip end, so that
the smoke can easily be drawn through that
10 perforation into the mouth without cutting off
the tip end, as now usual. I make use of a
tubular cutter to perforate the cigar, and a
standing rod to free the tubular cutter from
the tobacco, and I combine with this the cutter
15 for cutting off the outer end of the cigar,
so that both things can be accomplished by the
movement of one lever.

In the drawings, Figure 1 is a side view, with
the tubular cutter in section. Fig. 2 is a plan
20 view of the machine. Fig. 3 is a section with
a modified head to the tubular cutter, and Fig.
4 is an end view of the machine.

The tubular cutter *a* is made of steel, and it
is provided with a head, *b*, that is guided by
25 and slides within the barrel *d* upon the standard
e, and the base of this standard is recessed,
so as to be adapted to the reception of the ci-
gar-tip, which is to be perforated transversely.
There is a spring, *f*, that is within the barrel,
30 and acts beneath the cutter-head to raise the
same and withdraw the cutter from the cigar;
and there is a piece of wood inserted in the
base at *e'*, against which the tubular cutter is
pressed in finishing its cut. The rod *i* or dis-
35 charger is within the tubular cutter, and it is
stationary, and it frees the tubular cutter as it
rises from the tobacco that is cut out of the
cigar, and prevents it remaining within the
cutter and obstructing the same. The top end
40 of this discharger is attached to the top of the
barrel *d*. When the tubular cutter *a* is to be
worked by a direct pressure from the hand,
the rods *l* are attached to the head *b*, and ex-
45 tend through the top of the barrel and termi-
nate in a percussion-plate, *m*; but usually the
head *b* is made with an arm, *b'*, extending out
laterally through a vertical slot in the barrel
d, so that the cutter may be operated by the
50 lever *o*, shaft *p*, and slotted cam-shaped arm
q, that goes over the arm *b'*, extending out from
the cutter-head, and hence forces the cutter-

head and tubular cutter down to punch the
cigar. At the same time the cutter *r* is moved
by the lever *o* to cut off the outer end of the
cigar against the segmental bed-shear, upon 55
which the cigar is laid. The shaft *p* is sup-
ported in suitable bearings, *t*, upon the bed *t'*,
and there is a spring, *d'*, that acts to return
the shaft *p* and raise the cutter and move the
parts into a normal position after each cut has 60
been made. The slotted cam-shaped arm raises
the cutter so as to prevent its sticking in the
cigar. The cutter *r*, that removes the surplus
material at the outer end of the cigar, is of ordi-
nary construction, and receives its motion in 65
operating the shaft *p* by the lever *o*. The tubu-
lar cutter *a*, its standard *e*, and the slotted
cam shaped arm *q* are movable, so as to adapt
the machine to different lengths of cigars.

It will be apparent that this instrument is 70
adapted to the perforating of the cigar at the
same time that the rough end is cut off.

I am aware that a cutter has been thrust
transversely into the cigar-tip at the same time
that the outer end of the cigar is cut off; but 75
the tobacco springs back into the perforation,
and the smoking qualities of the cigar are not
improved.

In my invention the perforation is made by
a tubular cutter that removes the tobacco, so 80
that the hole cannot fill up.

The cutter *r*, its shaft *p'*, and spring *p'* have
heretofore been made.

A convenient way of applying my improve-
ment with this old cutter is to couple the end 85
of the shaft *p* to the end of the cutter-shaft *p'*,
and to provide an arm and handle, *o*, that pro-
jects from the shaft *p* and acts behind the han-
dle portion of the cutter *r*.

I claim as my invention—

1. The tubular cutter and head and the con-
taining-barrel and spring, in combination with
the stationary discharger and the bed upon
which the cigar is to be laid, the pivoted cam-
shaped arm *q* and lever to actuate the same, 95
and the arm *b'*, substantially as set forth.

2. The shaft *p*, cutter *r*, and handle *o*, and
the cam-shaped arm *q*, projecting from the
shaft *p*, in combination with the tubular cut-
ter and head, a discharger within the tubular 100
cutter, a support in which the cutter slides,
and a bed upon which the cigar is laid while

being acted upon by the tubular cutter *f* and the cutter *r*, substantially as set forth.

3. The combination, with the tubular cutter and the support for the same, the discharger, and the rest upon which the cigar is laid, of the pivoted open cam-shaped arm *q*, a lever to actuate the same, and a projecting arm, *b'*, at the side of the cutter, and against which the

cam-shaped arm *q* acts to move the same, substantially as specified.

10

Signed by me this 5th day of February, A. D. 1885.

ALBERT ANGELL.
